(57) **CLAIM**

The ornamental design for a fit over glasses, as shown and described.

DESCRIPTION

FIG. 1 is a top perspective view of the fit over glasses showing our new design;

FIG. 2 is a front view of the fit over glasses;

FIG. 3 is a back view of the fit over glasses;

FIG. 4 is a right side view of the fit over glasses;

FIG. 5 is a top view of the fit over glasses; and,

FIG. 6 is a bottom view of the fit over glasses.

The left side view of the fit over glasses is a mirror image of FIG. 4. No claim is made to the features of the fit over glasses shown in dashed lines.
